UNITED STATES PATENT OFFICE.

REUBEN A. SMITH, OF EAST WEARE, NEW HAMPSHIRE.

DESIGN FOR A TOY.

SPECIFICATION forming part of Design No. 12,283, dated May 24, 1881.

Application filed March 9, 1881. Term of patent 7 years.

To all whom it may concern:

Be it known that I, REUBEN A. SMITH, a citizen of the United States, residing at East Weare, in the county of Hillsborough and State of New Hampshire, have invented and produced a new and original Design for Toys; and I do hereby declare the following to be a full, clear, and exact description of the invention, such as will enable others skilled in the art to which it appertains to make and use the same, reference being had to the accompanying drawings, and to the letters or figures of reference marked thereon, which form a part of this specification.

15 My invention relates to designs for that class of toys known as "acrobats" or "gymnasts." The distinguishing features of my design consist in forming the body of such toys or figures with an elongated tapering projection at its lower rear end, representing the nether portion of its jacket, and in painting or printing upon each side of the head a supplemental face.

20 In the drawings, Figures 1 and 2 are opposite side views of my design.

25 A represents the body of the figure, which has a curved outline tapering to the point a. This figure is printed or colored to correspond

with the character represented, and is provided with openings a' a' for the pivots by which the limbs are attached.

30 The head B is formed with a face, b, in profile, and also has on each side a supplemental face, b', the whole being surmounted by a cap or head-dress, c, appropriate to the character. The faces on opposite sides are drawn and colored to represent different characters.

35 One side of the figure may represent an Indian, while the opposite represents a Chinaman; or any fanciful characters desired may be shown on the opposite sides.

40 When mounted in a suitable frame, so as to perform gymnastic evolutions when operated in any of the usual ways, the figure forms a grotesque and amusing toy.

I claim—

45 The design for toys herein shown and described.

In testimony whereof I affix my signature in presence of two witnesses.

REUBEN A. SMITH.

Witnesses:

A. R. BROWN,
PHILIP MAURO.
